UNITED STATES PATENT OFFICE.

CHARLES H. CLARK, OF SAN FRANCISCO, CALIFORNIA, ASSIGNOR TO STANDARD GEAR MOTOR COMPANY, OF PHOENIX, ARIZONA, A CORPORATION OF ARIZONA.

ROTARY ENGINE.

1,058,153.

Specification of Letters Patent.

Patented Apr. 8, 1913.

Application filed May 26, 1909. Serial No. 493,579.

To all whom it may concern:

Be it known that I, CHARLES H. CLARK, a citizen of the United States, residing in the city and county of San Francisco and State of California, have invented a new and useful Improvement in Rotary Engines, of which the following is a specification in such full and clear terms as will enable those skilled in the art to construct and use 10 the same.

My invention relates to fluid pressure engines or motors of the gear-tooth type, wherein the teeth of the gears act as pistons and are propelled by the pressure of a confined fluid and not by its impact. The engine is not of the impulse type for the teeth are not used as vanes wherein a jet of fluid is directed to strike against them as in a 15 turbine engine.

20 The engine has for its object to provide an improved motor of the character stated, having means for running at high speeds and under high pressures, as well as under low speeds and pressures, for keeping the 25 gears in alinement in any position of the engine, which may be regulated by the braking action of a retarded exhaust, which may be operated by superheated steam or by cold fluids, which may be reversed without altering 30 the adjustment of the centerpiece to the gears, which may have the directions of the entering fluid and discharging fluid in line with the direction they must follow in the engine, and wherein the centerpiece can be 35 adjusted to the sides and curved faces of the gears before being clamped in place.

Another object of my invention is to provide a combination fluid pressure engine and pump.

40 Another object of my invention is to provide a motor that in its various forms may be used as a pump.

Another object of my invention is to provide in a device of the character described 45 means for compensating the thrust on the bearings.

Another object of my invention is to provide a device of the character referred to, and means for compounding the same.

Other objects will appear in the following 50 description and claims.

I attain my objects by the means illustrated in the accompanying drawing of which:

Figure 1, is a side elevation of my engine 55 in its simplest form; Fig. 2, a side elevation of my engine incased; Fig. 3, a horizontal central section through case of Fig. 2; Fig. 4, an end elevation of Fig. 2, showing pulley inside the bearings; Figs. 5 to 12 inclusive 60 are detail views of my centerpiece and parts thereof showing modifications for various uses; Fig. 13, a diagrammatic view of the piping ordinarily used in my device in connection with my centerpiece, showing pipe 65 50^a utilized to exhaust the main part of the fluid from any part of the outer inclosing case shown in Figs. 2, 3 and 4; Fig. 14, a fragmentary, enlarged view of the gear-wheels about their point of intermeshing; 70 Fig. 15, a diagrammatic view of the piping for use with the centerpiece of the type shown in Fig. 10; Fig. 16, a diagrammatic view of the piping for compounding a number of my engines; Fig. 17 is a vertical sec- 75 50^b tional view of my engine taken through the line x—y, Fig. 18; and Fig. 18 is a longitudinal central sectional view showing a modified form of case.

The same numeral of reference marks the 80 same part throughout the various views.

My invention consists in the novel parts, combinations and arrangements set forth in the following description and particularly pointed out in the claims.

Explaining my invention in detail, and referring to the drawings, I provide a pair of gear wheels 1, 2, which may be mounted in bearings 3, 4, fixed in a frame 5, leaving the gears uncovered excepting about the region of their intermeshing points; or inclosed in a case 6, a modified form of frame which besides completely covering the gears, may support the bearings.

For operating at high speeds, it is highly 95 desirable that the friction be reduced to a minimum; and I attain the desired result not only by making my gear teeth 7 rela-

tively small, but by leaving a clearance space between the sides of my gears and the inclosing structure, in the manner further described below.

5 Another reason for making the teeth small is that the space between the teeth is thus made but very little larger than the area of the tooth itself. As the size of the teeth is increased in comparison to the diameter of the gear, the space aforesaid becomes so large relatively to the teeth that the engine is not economical; for to be economical and theoretically perfect the area of the space should equal the area of the 10 tooth.

15 In devices of the character specified, friction plays an important part in their operation, especially when they are operated at high speeds. The friction between the teeth 20 themselves I diminish as aforesaid; but in similar devices hitherto, there has always been provision made for side and face contacts between the gears and the inclosing block, to avoid the leakage of steam, when 25 the fluid medium happens to be steam, along the sides and fronts of the gears. I further diminish the friction incident to said engines, by removing the side and face friction altogether, by leaving a clearance space 30 between the sides and faces of the gears and the inclosing block. This I find can be done and economically done at high speeds. For the rapid rotation of the teeth creates a 35 line of much less resistance along their course than exists along their sides and faces if the clearance is not more than say from one to three one-thousandths of an inch.

40 My engine operates by directing fluid pressure against the teeth of a pair of intermeshing gears; and the fluid pressure may be that of water, steam, compressed air or cold gases; and by water jacketing and supplying an igniter, the vapor of gasolene or 45 other explosive may be used. But I introduce, direct, and exhaust the fluid in an improved manner, which will be understood from the following description.

50 In combination with the gear wheels aforesaid I provide a centerpiece 8, which may be made in various forms but which possesses these most important features; that it is always stationary, immovable, and rigidly secured, and this allows fine permanent 55 adjustments for running my engine at high speeds; and need not be moved to reverse the motor; that it allows the exhaust to be used for compensating the thrust on the bearings; that it allows several engines 60 to be compounded; and that it can be adjusted to the curved faces of the gears before being clamped.

Looking at Fig. 1, which shows the unincased type of my device, it will be seen

that there is a one piece casting 9, which is 65 the same, on each side of the gear wheels, and holds the complete engine together. By means of the bolts shown therein the whole frame 5 and centerpiece 8 become 70 like one solid block; and the machine can be operated whether it is lying on its side or standing upright, without the centerpiece losing its alinement, as would not be the case with similar machines using steam balanced side walls. For such walls would be 75 forced against an uneven surface by the weight of the gears and this would cause a serious leak.

80 In the centerpiece illustrated in Fig. 1, the entrance port for the fluid pressure is shown at 10, which is situated a little below the line joining the centers of the two gears. By this arrangement a downward pressure is exerted on the teeth below it, and an upward pressure on the teeth above, as is apparent 85 from Fig. 14. The force acting on the gears is proportional to the pressure into the area of the teeth acted on; and as one tooth of one gear is always covering one tooth of the other gear above the entrance port, the 90 covered tooth is not acted on by the pressure. Consequently the downward pressure on that gear is not balanced by an upward pressure, as it is on the gear having the tooth in the lower or covering position, and 95 it is therefore moved downwardly. The force moves from one gear to the other as the gears rotate, alternately back and forth, and produces a continuous rotation. The plate 11, see Fig. 7, and the back 49 of centerpiece 8, see Fig. 8, are disposed closely 100 against the sides of the gear wheels, leaving a clearance of from one to three one-thousandths of an inch as aforesaid.

105 The fluid escapes directly into the air or into a receiver. Now, in their rotation, the gear teeth gather air about the region above the meshing point; and this air they compress as they move downwardly, thus producing a retarding effect on the engine. To 110 avoid this effect I provide an escape port 12 in either or both the front and back of my centerpiece through which the air may escape.

115 Attention is now directed to the block 13, forming part of my centerpiece. The function of said block is to create with the front and back of the centerpiece and the bottoms of the spaces between the gear teeth, curved channels for directing the fluid pressure 120 against the teeth, with or without exhaust ports within the centerpiece. The blocks are formed integrally with the centerpiece, but for the reasons aforesaid, they do not quite touch the faces of the teeth, the necessary 125 adjustments being made by means of the bolts 14 and 16. Bolts 15 passing through the blocks and the front and back of the

centerpiece, and through the frame when incased secure the whole in a rigid state, which may be made accurate in position with respect to the sides of the gears by 5 means of the thin metal adjusting sheets 17, 18. Any of the types of centerpiece shown in the drawing may be used in either the inclosed or uninclosed form of my engine. But where reversals are desired a double 10 block may be used, one above the line of gear centers and one below it, forming two sets of channels, an upper and lower, as shown in Fig. 18. By the described arrangement I provide means for reversing 15 my engine without moving the centerpiece; and an immovable centerpiece is necessary, especially for high speed machines, since the adjustments to avoid friction on the one hand and leakage on the other must be very 20 fine.

It is to be understood that reversals may be made by putting pressure in the case even where only one block is used; but such proceeding is attended with the disadvantage that if any play exists on the bearings, 25 the gear locks on the centerpiece, and the case would have to be unduly heavy to stand the pressure. Therefore, two blocks are used as stated, and the gear wheels turn 30 with equal efficiency in either direction.

Referring to the means for braking my engine. This is done by partially or wholly closing the exhaust port. Whenever the exhaust port is partially closed, said exhaust 35 port being the entrance port of the reversal pressure, as by the valve 27 for instance, the pressure in the centerpiece rises and the force acting on the gears is lessened, since that force is equal to the difference between 40 the pressure at the entrance port and pressure inside the centerpiece.

While under certain conditions it is not necessary to cause the fluid to enter and discharge without abruptly altering its direction in the engine, under conditions of 45 high speed it is extremely expedient that it do so. The entrance and exhaust ports in Fig. 1 show how the pipe 10', carrying the entering fluid and the discharge pipe *p* are in line with the direction that the fluid must follow in the engine.

My engine can be operated as a combined pump and motor. This is done by simply immersing the engine in the fluid to be 55 pumped, using the double block. The driving fluid is introduced in the usual manner at the entrance port on the opposite side of the meshing point of the two gears. The operating fluid pressure escapes into and 60 out of the liquid to be pumped and the gears force the liquid into the other port and raise it continuously to any desired height.

Referring now especially to be inclosed type of my engine and looking at Fig. 2

and Fig. 3. It will be observed that my preferred type of case consists of three parts 65 19, 20 and 21. Part 19 incloses the back, side, bottom and top of my engine. The three parts of the case are suitably bolted together. Another type of case is shown in 70 Fig. 18. This type has a reinforcing rib 50 running entirely around it, formed of flanges on the upper and lower parts, bolted together. The top of the case lifts up and the gear wheels on each shaft can be at- 75 tended to without disturbing the other gear wheels. This form thus possesses advantages which make it possible to use many gear wheels on each shaft. The rib around this case also acts to create an even expansion 80 in the case, thus holding the bearings parallel.

Returning now to my centerpiece and looking more in detail to the block. These blocks are arranged as aforesaid to provide 85 curved channels for the movements of the pressure fluid. The fluid enters the engine at the port 10 and passes through these channels. The exhaust takes place in two ways either through the exhaust port 22 90 (Fig. 18) situated near these channels and communicating therewith; or into the case and out at the opposite port 26, that is to say, the port that becomes the entrance port on reversal. In the latter arrangement part 95 of the pressure goes out at the usual exhaust port near the channel and part remains in the case creating therein a pressure which has an important function. It will be noted that the pressure after entering and while 100 in the channel exerts a thrust on the bearings which thrust must ordinarily be resisted by the strength of the bearings; but by providing a pressure in the case a resultant pressure is produced which acts on 105 the bearing in the opposite direction and with nearly equal force to the pressure from the channels, thus counter-balancing the thrust on the bearings. Explaining this counterbalancing effect more in detail, the 110 fluid entering by way of the port 10, Fig. 18, exerts a pressure on the gears until relieved by the escape of the fluid through the channels or passages 22^a, 22^b into the exhaust port 22. This relief of the pressure 115 is only partial, as only part of the fluid reaches the exhaust port 22. The remainder escapes into the casing as the teeth pass the edges 8^a, 8^b of the lower block 8 and, flowing around the gears, exerts on the gears a 120 pressure in a direction substantially opposite to that of the pressure first mentioned. The port 22' being closed, the fluid inside the casing can escape only by way of the port 26 and can reach this port only by pro- 125 pelling the gear teeth past the edges 8^c, 8^d of the upper block 8, thereby aiding in revolving the gears. It will therefore be seen

that the pressure in the casing, produced by throttling the exhaust port 22, is not a back pressure, in the sense that it retards or impedes the rotation of the gears. In fact, 5 throttling the exhaust port 22 has the effect of dividing the pressure fluid: part having a propelling action on the gears on one side of the line joining their centers and the other part having a propelling effect on the 10 other side of said center line. The ports 10 and 26 may therefore be appropriately termed driving ports, since the fluids passing through them act to propel the gears. At the same time this last port exerts on the 15 gears a thrust in a direction substantially opposite to that produced by the other port; the resultant or ultimate thrust on the gear bearings being the difference between the two thrusts. In order, however, to have the 20 internal pressure exerted in a counterbalancing direction the pressure fluid must escape into the casing at points less than 90° from the aforesaid center line and must enter the teeth again at points less than 90° 25 from said line. This means that in the construction illustrated in Fig. 18 the edges 8^a, 8^b, must be less than 90° below, and the edges 8^c, 8^d, less than 90° above, the center line; the centers or apexes of these arcs or 30 angles being at the axes of the gears. It is also essential that the side walls of the inclosing centerpiece be stationary or immovable so that the pressure in the casing 35 cannot press either wall against the adjacent faces of the gears.

The fluid pressure is introduced and exhausted by means of the pipe line shown in Figs. 13 and 15. The fluid enters at 23, flows in the direction of the arrows into entrance port 10, or entrance port 26 according to the position of the valve 27. With the 40 valve as shown in the drawing, the pressure after passing through the pressure channels, exhausts through either or all of the ports 22, 22' and 26 and into the air through pipe 30.

When it is desired to compound my engines, the pipe line shown in Fig. 16 and the connections therewith are arranged as 50 shown and specified. The exhaust from the first engine passes through pipes 31, 32 and 46; that from 31 entering the second engine through valves 33, 34 and 35 into port 10 and passing therefrom through pipe 36 into 55 the air or condenser through the pipe 37 also through pipe 38 valve 35 pipe 39 valve 40 pipe 43 into port 10 of the third engine and passing therefrom through pipe 48 into the air or condenser also through port 26 60 pipe 44 valve 40 and pipe 45 into the air or condenser. Another portion of the exhaust from the first engine travels direct therefrom into the third engine through port 10 in the following manner; through pipe 32

valve 41 pipe 42 where it mixes with exhaust from the second engine and enters valve 40 pipe 43 into port 10 as before stated. The second and third engines are progressively increased in size in their proper ratio. Steam or other expansive fluid pressure media, may thus be used expansively. The engines may be compounded in the ordinary way of carrying the fluid direct from one to the other; but the above described mode of compounding has advantages, among which 70 is the fact that each engine is connected with a condenser and not only receives added power therefrom but it will be noted that a considerable portion of the fluid pressure is expansively used through several stages in 75 each engine and exhausted directly into the air or condenser wherefore it is not necessary to construct the intermediate or low engine nearly so large as would ordinarily be the case where the steam is carried directly from one to the other. Thus it is possible to compound a gear engine of this type and yet have no back pressure whatever on either the high or intermediate cylinder. All the gears may be mounted on the 80 same two shafts having teeth of a different depth or gears of a different width, or they may all be mounted on one shaft having gears of a different diameter as well as width, or they may be all allowed to run independently of each other at any desired speed.

Returning now to the consideration of the forms of my centerpiece and their parts illustrated in Figs. 5 to 12 inclusive, it will 100 be noted that my centerpiece is made up of two parts, a front 11 and a back 49. The front illustrated in face view in Fig. 7 is attached to the back by appropriate screws or bolts, as indicated in Fig. 8. The use of 105 the escape port 12 in the front and back plates has already been explained. Fig. 5 shows the back plate used where it is not desired to reverse the engine, and where the exhaust takes place directly from the centerpiece into the air. Fig. 6 shows a side view of such construction, 22 being the exhaust pipe. In the back shown in Fig. 8, the exhaust takes place from the ends of the steam channels and not through the block 115 13. Fig. 9 is a side view of the centerpiece arranged in this manner, the pipes shown therein illustrating the mode of introducing the pressure fluid through both the front and back plates.

Fig. 10 shows a back plate constructed in the manner shown in side view of Fig. 15. It is designed for a double block, the front plate being shaped as illustrated, the joints occurring at 17 and 18.

Fig. 11 illustrates the manner in which the fluid is introduced and exhausted in line with the course it takes in the centerpiece.

The same figure illustrates a construction in which both the blocks 13 and 13' are made integral with the back plate, 49 and frame 5 or 6; 49' showing the combined back plate 5 and frame. In such construction my gear wheels are adjusted to blocks 13 and 13' by means of adjustable bearings.

Fig. 12 illustrates the front or back plate shown in Fig. 13, which in this construction are the same provided each one has the ports through it.

By the words "immovable", "stationary", and like terms applied to the centerpiece or parts thereof in the following claims I do 15 not mean that such elements are necessarily non-adjustable, or non-detachable, but, in general, that they are rigidly fixed in position to the extent that they cannot be moved or shifted by the pressure or impact of the 20 driving fluid.

I claim:

1. A gear-motor comprising intermeshing gear-wheels, an immovable centerpiece inclosing the parts of said gear-wheels adjacent to their meshing point, and having channels for directing the pressure fluid against the teeth of said gear-wheels, and a frame for supporting said centerpiece and said gear-wheels.

2. A gear motor comprising intermeshing gear-wheels, immovable centerpiece inclosing the parts of said gear-wheels, adjacent to their meshing point, a block fixed in said centerpiece having curved faces adapted to 30 form with the sides of said centerpiece and the bottoms of the spaces between the gear teeth channels for directing the pressure fluid against the teeth of said gear-wheels, and a frame for supporting said centerpiece.

3. A gear motor comprising intermeshing gear wheels, an immovable centerpiece inclosing the parts of said gearwheels adjacent to their meshing point, a block fixed in said centerpiece on one side of said meshing point having curved faces adapted to form with the sides of said centerpiece and the bottoms of the spaces between the gear teeth channels for directing the pressure fluid 45 against the teeth of said gear wheels, and having an entrance port for the pressure fluid, a second block on the other side of said meshing point fixed in said centerpiece and having similar curved surfaces similarly 50 adapted, and having an entrance port for the fluid pressure; and a frame for supporting said centerpiece.

4. A gear motor comprising intermeshing gear wheels, an immovable centerpiece inclosing the parts of said gear wheels adjacent to their meshing point, a block fixed in said centerpiece having curved faces adapted to form with the sides of the centerpiece and the bottoms of the spaces between the

gear teeth channels for directing the pressure fluid against the teeth of said gear wheels, and having an entrance port for said pressure fluid and an exhaust port therefor on the same side of the said meshing point, and a frame for supporting said centerpiece. 65 70

5. A gear motor comprising intermeshing gear wheels, an immovable centerpiece inclosing the parts of said gear wheels adjacent to their meshing point, and having channels for directing the pressure fluid 75 against the teeth of said gear wheels, and a combined supporting frame and inclosing case for inclosing said centerpiece and gear wheels and for supporting the same.

6. A gear motor comprising intermeshing gear wheels, an immovable centerpiece inclosing the parts of said gear wheels adjacent to their meshing point, a block fixed in said centerpiece having curved faces adapted to form with the sides of said centerpiece 85 and the bottoms of the spaces between the gear teeth, channels for directing the pressure fluid against the teeth of said gear wheels; and a combined supporting frame and inclosing case for inclosing said centerpiece and gear wheels and for supporting the same. 90

7. A gear motor comprising intermeshing gear wheels having journals, a frame supporting said journals, a centerpiece rigidly bolted to said frame, inclosing the parts of said gear wheels adjacent to their meshing point, and a fixed block in said centerpiece having curved faces adapted to form with the sides of said centerpiece and the bottoms 100 of the spaces between the gear teeth, channels for directing the pressure fluid against the teeth of said gear wheels.

8. A gear motor comprising intermeshing gear wheels, an immovable centerpiece inclosing the parts of said gear wheels adjacent to their meshing point, an inclosing case, and means for operating said gear wheels and counterbalancing the thrust on their bearings, consisting of a block fixed in 105 said centerpiece having curved faces adapted to form with the sides of said centerpiece and the bottoms of the spaces between the teeth, channels for directing the pressure fluid against the teeth of said gear wheels, 110 and having an entrance port for the fluid pressure and a partially closable exit port therefor adjacent thereto, whereby when said exit port is partially closed, the pressure rises in the case and acts oppositely on the 115 bearings to the action of the fluid pressure in said channels.

9. A gear motor comprising a frame, intermeshing gear wheels and means for applying fluid pressure to said gear wheels 125 consisting of a front and back plate rigidly bolted together and rigidly fixed to the frame, and having an escape port on one

- side of the intermeshing point, each of said plates being adjusted to leave a small clearance between itself and the sides of the gear wheels; a block having curved faces conformable to the faces of the gear teeth and adjusted to leave a small clearance therebetween, and having an induct port on the other side of the intermeshing point.
10. In a gear motor, a pair of intermeshing gear wheels, curved channels for directing the fluid pressure against the teeth thereof, and means for introducing and exhausting said fluid pressures consisting of pipes arranged substantially tangentially to said curved channels.
11. A gear motor comprising intermeshing gear wheels and rigidly fixed means for delivering and exhausting a fluid pressure medium to and from said gear wheels having a portion about the region of intermeshing in proximate contact with the sides and faces of said gears, and a portion away from said region spaced away from the sides and faces of said gears.
12. In a gear motor, rigidly fixed means for delivering and exhausting a fluid pressure medium to and from said gear wheels having a relief opening and having a portion about the region of intermeshing in proximate contact with the sides of said gears, and a portion away from said region spaced away from said gears.
13. A gear motor comprising intermeshing gear wheels, a centerpiece inclosing the parts of said gear wheels adjacent to their meshing point, an inclosing case, and means for operating said gear wheels and counterbalancing the thrust on their bearings consisting of a block fixed in said centerpiece having curved faces adapted to form with the sides of said centerpiece and the bottoms of the spaces between the teeth, channels for directing the fluid pressure against the teeth of said gear wheels, and having an entrance port for the fluid pressure and a partially closable exit port therefor adjacent thereto, whereby when said exit port is partially closed, the pressure rises in the case and acts oppositely on the bearings to the action of the fluid pressure in said channels.
14. In a gear motor having a centerpiece, means for accurately adjusting the position of said centerpiece consisting of thin metal strips located between the joints thereof.
15. A gear motor comprising intermeshing gear wheels, and an inclosing case, a plate in proximate contact with the sides of said gear wheels about the region of their intermeshing, having a portion arranged for delivering and exhausting a fluid pressure medium to and from said gear wheels in proximate contact with the other sides and the faces of said gear wheels about the region of their intermeshing, and a portion away from said region spaced away from both the faces and sides of said gear wheels.
16. In a gear motor, the combination of intermeshing gears; an inclosure for the gears, provided with stationary walls closely adjacent to the faces of the gears about the point of intermeshing, and provided with driving ports for the driving fluid on opposite sides of the line joining the centers of the gears and with an exhaust port; and blocks arranged on opposite sides of said line between the said walls and forming in conjunction with the gears pairs of channels for the driving fluid, one pair of channels delivering fluid into the inclosure at points less than 90° from said center line and the other pair receiving fluid from the inclosure at points less than 90° from said line.
17. In a gear motor, the combination of intermeshing gears; a casing inclosing the gears, having an exhaust port and having driving ports for the driving fluid on opposite sides of the lines joining the centers of the gears; and a centerpiece comprising stationary side walls inclosing the gears about the point of intermeshing, and blocks on opposite sides of the said line, forming in conjunction with the gears pairs of channels for the driving fluid, one pair delivering fluid into the casing at points less than 90° from said center line and the other receiving fluid at points less than 90° from said line.
18. In a gear motor, the combination of intermeshing gears; a centerpiece inclosing the gears about the point of intermeshing, comprising stationary side walls on the opposite sides of the gears and blocks on opposite sides of the line joining the centers of the gears, said blocks being formed with curvilinear faces forming in conjunction with the gears channels for the driving fluid terminating at points less than 90° from the said center line; and an inclosure for the whole, having an exhaust port; a port between one of said blocks and said center line to deliver driving fluid to the gears and a port between the other block and said center line to discharge driving fluid from the gears.
19. In a gear motor, the combination of intermeshing gears; an inclosure for the gears having an exhaust port and having driving ports for the driving fluid on opposite sides of and close to the point of intermeshing of the gears; and a center piece inclosing the gears about the point of intermeshing, composed of parts incapable of being moved by the driving fluid and constructed to deliver driving fluid into and receive driving fluid from the inclosure at points less than 90° from the line joining the centers of the gears.
20. In a rotary engine, the combination of intermeshing gear wheels; and a centerpiece

having normally fixed parts incapable of being moved by the fluid supplied to drive the engine, closely inclosing the gears about the point of intermeshing and at other points 5 leaving space around the gears for free movement of the driving fluid.

21. In a rotary engine, the combination of intermeshing gears, and a combined centerpiece and frame, a portion of the centerpiece 10 being detachable and adjustable with respect to the gears for the purpose set forth.

22. In a rotary engine, the combination of intermeshing gears; an inclosing case one side of which is closely adjacent to the sides 15 of the gears around their point of intermeshing; and a member on the opposite side of the gears, adjustable with respect thereto and incapable of being moved by the driving fluid.

23. In a rotary engine, the combination of intermeshing gears; walls inclosing the sides of the gears adjacent to their meshing point; and adjusting sheets for accurately spacing said walls with respect to the sides 25 of the gears.

24. In a gear engine, the combination of intermeshing gears; an inclosing case having a portion in proximate contact with the faces and one of the sides of each of the 30 gears; and a plate in proximate contact with the other sides of the gears.

25. In a gear engine, the combination of intermeshing gears; a casing inclosing the gears, having an exhaust port and having 35 driving ports on opposite sides of the meshing point of the gears; a supply pipe for conveying driving fluid to the engine; branch pipes connecting the supply pipe with the driving ports; means controlling 40 said pipes, whereby the driving fluid may be caused to flow into either driving port and out of the other, at will, whereby to reverse the engine; a pipe connected to the branch pipes at their juncture to convey 45 fluid away from the engine; and a pipe connecting the last named pipe with the said exhaust port.

26. In a gear engine, the combination of intermeshing gears; a casing inclosing the 50 gears, having exhaust ports and having driving ports on opposite sides of the meshing point of the gears; a supply pipe for the driving fluid; branch pipes connecting the supply pipe with the driving ports; 55 means for directing the driving fluid into either branch pipe at will; and exhaust pipes for carrying away the exhaust from the exhaust ports.

27. In a compound gear engine, the combination of intermeshing gears; a casing inclosing the same, having driving and exhaust ports, the driving ports being on opposite sides of the meshing point of the gears; a supply pipe for driving fluid, and

means for connecting the same with either 65 driving port at will; a second set of intermeshing gears; a casing therefor, having driving and exhaust ports, the former being located on opposite sides of the meshing point of the gears; and means for conveying 70 exhaust driving fluid from the first set of gears to either driving port of the second set at will.

28. In a compound gear engine, the combination of intermeshing gears and a casing 75 inclosing the same, having driving and exhaust ports, the driving ports being located on opposite sides of the meshing point of the gears; a supply pipe for driving fluid, and means for connecting the same to either driving port at will; a second set of intermeshing gears and a casing therefor, having driving and exhaust ports, the former being located on opposite sides of the meshing point of the gears; a third set of intermeshing 80 gears and a casing therefor, having similarly located driving ports and an exhaust port; means for delivering exhaust driving fluid from the first set of gears to the second and third sets of gears and to either driving port 90 the said second and third sets, simultaneously; and means for delivering exhaust driving fluid from the second set of gears to either driving port of the third set, simultaneously with the delivery thereto of exhaust 95 driving fluid from the first set.

29. In a compound gear engine, the combination of a plurality of sets of intermeshing gears; casings inclosing the sets of gears, provided with driving and exhaust 100 ports, the driving ports being located on opposite sides of the meshing points of the respective gears; a supply pipe for driving fluid, and means for connecting the same at will with either driving port of the first set 105 of gears; means for connecting an exhaust port of the first set with either driving port of the second set at will; and means for delivering exhaust driving fluid simultaneously from the first and second sets to either 110 driving port of the second set.

30. In a compound gear engine, the combination of a plurality of sets of intermeshing gears and casings inclosing the same, having driving and exhaust ports, the driving 115 ports being located on opposite sides of the meshing points of the respective gears; a driving fluid supply pipe, and means for connecting the same at will to either driving port of the first set of gears; piping for conveying exhaust driving fluid from an exhaust port of the first set to the second set, and means for delivering driving fluid from said pipe to either driving port of the second set at will; and piping for conveying exhaust driving fluid from another exhaust port of the first set and from an exhaust port of the second set to the third set, and means 120 125

for delivering driving fluid from said piping to either driving port of the said third set at will.

31. In a compound gear engine, the combination of a plurality of sets of intermeshing gears and casings inclosing the same, having driving and exhaust ports, the driving ports being located on opposite sides of the meshing points of the respective gears; 5 a supply pipe for driving fluid, an exhaust pipe, branch pipes between the said pipes and the driving ports of the first set of gears, and a valve for connecting the supply pipe at will with either driving port and 10 the exhaust pipe with the other driving port of the said first set; and piping connecting exhaust ports of the first set to the driving ports of the third set, pipes connecting exhaust ports of the second set to said piping, 15 pipes connecting said piping with the driving ports of the second set, and valves controlling the flow of driving fluid through said pipes and piping.

32. In a compound gear engine, the combination of high, intermediate and low pressure sets of gears; casings for the gears, having centerpieces provided with stationary parts inclosing the gears about the meshing points of the gears, means for supplying 25 driving fluid to the high pressure set of gears; and means for supplying exhaust driving fluid from the high pressure set to the intermediate and low pressure sets, and from the intermediate to the low pressure 30 set.

33. In a compound gear engine, the combination of a plurality of sets of intermeshing gears; casings for the gears, having centerpieces composed of stationary parts 35 inclosing the gears about their meshing points and elsewhere leaving space around the sides and faces of the gears for unimpeded movement of the driving fluid; means for delivering driving fluid to the first set of 40 gears; and means for conveying a portion of the exhaust driving fluid from the first set to a succeeding set.

34. In a compound gear engine, the combination of a plurality of sets of intermeshing 50 gears; centerpieces for the gears, composed of stationary parts inclosing the gears about their meshing points and elsewhere leaving space around the sides and faces of the gears for unimpeded movement of the driving fluid; the centerpiece for the first set of gears having a driving port and an exhaust port on the same side of the meshing point of the gears; and means for conveying exhaust driving fluid from said exhaust 55 port to a succeeding set of gears.

35. In a compound gear engine, the combination of a plurality of sets of intermeshing gears, and means for utilizing exhaust driving fluid from the first set of gears to

drive a succeeding set and simultaneously 65 counterbalance the driving pressure on the first set.

36. A compound rotary engine of the gear tooth type, having gears that are only partly inclosed on their sides and faces by the inner 70 construction, for the purpose of directing a fluid pressure medium against the teeth of said gears near their meshing point; a high pressure inlet and intermediate and low pressure outlets; and an inlet connection to a second set of gears from said intermediate pressure outlet.

37. A compound rotary engine of the gear tooth type, having gears that are only partly inclosed on the sides and faces by the inner 80 construction, for the purpose of directing a fluid pressure medium against the teeth of said gears near their meshing point; an inlet port and a plurality of outlet ports with fluid receiving means communicating 85 between the successively lower sets of gears, delivering said fluid pressure at successively lower pressures to the ports of each respective set of said gears.

38. In a device of the class described, the combination of intermeshing gear wheels and a center piece inclosing the sides of said gear wheels adjacent to their meshing points, the center piece being made in parts adjustable toward and from each other so as to vary 95 the fit of the parts on the sides of the gears, and means for securing the parts in adjusted position.

39. In a device of the class described, the combination of intermeshing gear wheels 100 and a center piece inclosing the sides of said gear wheels adjacent to their meshing points, the center piece being made in parts adjustable toward and from each other, and sheets of spacing material insertible between the parts of the center piece so as to vary the fit of parts of the center piece on the sides of the gears, and means for securing the parts in adjusted position.

40. In a device of the class described, the combination of a case provided with intake and exhaust openings, containing intermeshing gear wheels, the gears being located within the case at a substantial distance from the walls thereof, and a normally 115 stationary center piece within the case connected to the intake opening of the case, inclosing the circumferences and having normally stationary side walls inclosing and in approximate contact with the sides of the 120 gears adjacent to their intermeshing points and provided with channels for directing the pressure medium admitted through the intake opening against the teeth of said gear wheels.

41. In a device of the class described, a fluid tight case having inlet and outlet pipes, a pair of shafts, a gear wheel carried by each

shaft, a fixed center piece secured to the case at the point of intermeshing of the two gears and having an opening in register with one of the openings in the case, and means to adjust the center piece.

42. In a device of the class described, a pair of intermeshing gears, a shaft for each gear, a fluid tight case having an inlet and an outlet, a center piece made in two pieces secured to the case at the junction of the two gears, said center piece covering one of

the openings in the case, and means to adjust one of the pieces of the center piece with respect to the other.

In testimony whereof I have set my hand 15 in the presence of the two subscribed witnesses.

CHARLES H. CLARK.
